(57) CLAIM

I claim the ornamental design for multi-functional auto detailing system, substantially as shown.

DESCRIPTION

FIG. 1 is a front elevation view of a multi-functional auto detailing system showing my new design.

FIG. 2 is a front elevation view thereof with control panel removed.

FIG. 3 is a right side elevation view thereof.

FIG. 4 is a left side elevation view thereof.

FIG. 5 is a rear elevation view thereof.

FIG. 6 is a top plan view thereof; and,

FIG. 7 is a bottom plan view thereof.

The broken lines are shown for illustrative purposes only and form no part of the design.
